UNITED STATES PATENT OFFICE.

GEORGE E. ROESCH, OF PITTSBURGH, PENNSYLVANIA.

AUTOMATIC LIGHTNING SWITCH FOR RADIOS.

Application filed August 18, 1924. Serial No. 732,691.

The present invention relates to an automatic lightning switch for radios, one of the objects of which is to prevent lightning from entering a building through the lead 5 in wire of an aerial connected to a radio set in the building.

A further object of the invention is to provide a switch through which either the aerial and set may be placed in circuit or 10 through which the aerial and ground may be placed in circuit at the option of the user.

A still further object of the invention is to provide a switch through which a radio aerial is placed in circuit with a radio set, 15 the switch automatically connecting the aerial with the ground when the aerial is disconnected from the set.

The above and other objects of this invention will be apparent from the following 20 description of the present preferred form of the invention taken in connection with the accompanying drawings wherein:—

Fig. 1 is an elevational view of a switch constructed in accordance with this invention illustrating its application;

Fig. 2 is a vertical sectional view of the same;

Fig. 3 is a detail fragmentary sectional view of the switch illustrating its application; and

Fig. 4 is a detail elevational view of the switch block showing the key receiving recess thereof.

In order to illustrate the application of 35 this invention a portion of a building 5 is fragmentarily shown the inside of which is designated 6 and the outside 7, the outside of the building being provided with a recess 8.

40 Mounted on the outside 7 of the building is a switch block or base 9 made of hard rubber or other suitable insulating material which has an opening 10 formed therein near its upper terminal which registers with the recess 8 in the outside of the building. The lower end of the switch block is provided with a key slot 11 the outer end of which terminates in a key receiving recess 12 while the inner end communicates with 45 an opening 13 formed through the wall of the building 5.

50 Detachably mounted on the outer face of the block 9 near the free end thereof is a pair of lugs 14 between which a switch bar 15 is pivotally mounted. One end of the switch bar is pivotally mounted as indicated

at 16 between the furcations in the enlarged end 17 of a floating rod 18. The inner end of the rod 18 is mounted in the opening 10 of the switch block 9 and may be moved through the latter and into the recess 8 when the switch bar 15 is moved into the dotted line position shown in Fig. 2 of the drawings. The opposite end of the switch bar 15 is movable between and engageable with lugs 19 detachably mounted on the lower end of the switch block 9. The bar is normally held between the lugs 19 by means of a coil spring 20 which encircles the rod 18 and has the innermost convolution thereof engageable with the switch block 9 while the outer convolution impinges against a washer 21 mounted on the outer end of the rod 18.

One of the lugs 14 is adapted to receive one end of a wire 22 which leads to the 75 aerial while one of the lugs 19 is adapted to receive one end of a wire 23 which leads to the ground. Consequently, an electrical circuit may be completed from the aerial through the lugs 14, switch bar 15, lugs 19 80 and wire 23.

When it is desired to connect the aerial wire 22 with a radio set or instrument the lower end of the switch bar 15 is urged outwardly so as to disengage the same from the lugs 19. This is accomplished through the medium of a switch key or rod 24 operable from the inside 6 of the building 5. The outer end of the switch key is adapted to engage a semi-spherical recess 25 formed 90 on the inner end of a cylindrical abutment 26 the latter being mounted on the switch bar 15 near the lugs 19. The key 24 includes a pin 27 which is movable through the opening 13 in the wall of the building 5, through the key slot 11 and into the key receiving recess 12 so as to hold the rod 24 in a fixed position to thereby correspondingly retain the switch bar disengaged from the lugs 19. The inner end of the switch rod or key is located within the building and is equipped with a knurled head 28 for convenience in manipulating said rod or key. A wire 29 is engaged with the switch rod or key near the head 28, said wire leading to the radio instrument or set. In use of this device 95 when it is desired to connect the aerial with the set or instrument the switch rod or key 24 is urged outwardly so as to disengage the bar 15 from the lugs 19 pursuant to which 100 the knurled head 28 is turned so as to position the pin 27 transversely across the key

100

115

slot 11 in the recess 12. The circuit is then completed from the aerial to the set by means of the wire 22, lugs 14, switch bar 15, switch rod 24 and wire 29. When it is no longer desired to use the set or instrument the knurled head 28 of the switch rod is turned to align the pin 27 with the key slot 11 thereby permitting the switch rod to be retracted into the building and corresponding-
ly permitting the switch bar 15 to be automatically reengaged with the lugs 19 under influence of the spring 20. Consequently, when the set is not being used, lightning, electrical surges or like phenomena coming in contact with the aerial will be induced into the ground through the wire 22, switch and wire 23.

It is of course to be understood that numerous changes may be made in this device in order to adapt the same for operation under various conditions. However, the device shown in the accompanying drawings illustrates the principle of the invention and I am aware that numerous modifications may

be made within the scope of the claims here- 25 to appended.

What is claimed is:—

1. A switch for radio apparatus including a switch embodying a switch bar, and a rod in electrical communication with the radio apparatus and in contact with the switch bar to operate the latter, said rod loosely engaging the bar and being unconnected thereto to permit separation of the rod and bar when the latter is in a closed position. 30

2. A switch for radio instruments including a base equipped with contact lugs, a spring pressed lever pivotally mounted on said base and normally engaged with said lugs, an abutment carried by said lever and provided with a recessed terminal, and a rod mounted in said base, in electrical communication with the radio instrument, and loosely engageable in the recess of said abutment for disengaging the lever from said lugs. 40 45

In testimony whereof I affix my signature.

GEORGE E. ROESCH.
